DETONATION SUPPRESSION PISTON FOR
INTERNAL-COMBUSTION ENGINES

Albert G. Bodine, Jr., Van Nuys, Calif.

Application February 25, 1952, Serial No. 273,275

8 Claims. (Cl. 123—191)

1

This invention relates generally to internal combustion engines and to means for suppressing irregular burning and detonation of fuel-air mixture therein. The invention is based on my discovery that detonation in combustion engines involves acoustic phenomena and can be alleviated by means of certain acoustic apparatus used in combination with the combustion chamber.

The present application is directed to improvements in the field covered by Patent No. 2,573,536, issued October 30, 1951, and entitled Engine Detonation Control by Acoustic Methods and Apparatus. The present application is a continuation-in-part of my application Serial No. 252,818, filed October 24, 1951, for Engine Detonation Control by Acoustic Methods and Apparatus, which latter application is a division of my parent application which resulted in said Patent No. 2,573,536. For a full discussion of the acoustic aspect of detonation in combustion, and my basic solution for controlling detonation in combustion, reference should be had to my said issued patent.

Only briefly stated herein, the present invention is based on the fact that detonation in an engine combustion chamber produces sound waves, a large part of which rise to high amplitude at resonant frequencies of the chamber, and on my discovery that the sound waves produce the various well-known and harmful manifestations of detonation. According to my basic invention, I inhibit or attenuate these harmful effects by interfering with or attenuating the high amplitude detonation-induced sound waves, and this is done by use in connection with the combustion chamber of acoustic attenuation means made responsive to the frequencies at which the detonation induced sound waves build up to high amplitudes. One type of acoustic attenuation means broadly disclosed in my patent involved an attenuative configuration given to the upper end portion of the piston.

The general object of the present invention is the provision of an improved detonation controlling sound wave attenuator means of the class involving the piston structure.

Another object is the provision of a piston type of detonation attenuator which is improved as regards attenuative response to the offensive sound wave frequencies encountered in combustion.

Still another object is the provision of a detonation attenuative configuration on the piston structure which is improved as regards practicability, freedom from difficulty by reason of

2

carbon accumulation, and ease of construction.

According to the present invention, there is formed in the side wall of the piston, in the area between the upper ring groove and the top of the piston, a multiplicity of cavities extending in a row entirely around the piston. These cavities function as Helmholtz resonator cavities. To furnish communication between these cavities and the combustion chamber, the land between the cavities and the top surface of the piston is relieved or set back slightly, that is, given a clearance from the cylinder wall of the order of .005" to .030". This clearance space constitutes the "neck" of the Helmholtz resonator. The cavities are made of one or more sizes to be resonant to the offensive detonation frequencies in the combustion chamber. These cavities function as resonant absorbers, and are effective when designed to respond to the resonant peaks of the combustion chamber, to completely kill or substantially attenuate the harmful acoustic effects of detonation.

The invention will be better understood from the following detailed description of an illustrative embodiment, wherein:

Figure 1 is a side elevation of a piston in accordance with the invention shown in the cylinder of an engine;

Figure 2 is a top plan view of the piston, and

Figure 3 is a section of the piston on line 3—3 of Figure 1.

An engine cylinder is shown at 7, opening into combustion chamber 8, and the piston of the invention is designated by the numeral 9. The side wall 10 of the piston is shown to have ring grooves 11, and above the top groove, a setback circumferential land 12 extending to the piston top, the diameter of this land being slightly less than the diameter of the main body of the piston, so as to leave a slight clearance space, typically .005" to .020", between the land 12 and the cylinder wall 13.

Sunk into this land 12 are a multiplicity of cavities, here shown in two sizes, such as 14 and 15, the cavities extending in a row entirely around the land 12. The cavities are preferably relatively close spaced to one another, so as to achieve as much coverage as possible. They are of different sizes, calculated or selected to be responsive to previously determined resonant frequencies of the combustion chamber.

In the present embodiment, the cavities 14, which extend half-way around the piston, are designed to be responsive to a fundamental resonant frequency of a test chamber, and they

are in the nature of flat-bottomed slots, $\frac{5}{8}$ " in length, $\frac{1}{16}$ " wide, $\frac{1}{4}$ " in depth, and the ends are rounded, as illustrated. The cavities 14, responsive to an offensive harmonic of the test chamber, are round holes with flat bottoms, $\frac{1}{16}$ " in diameter, and $\frac{3}{16}$ " deep.

In operation, the sound waves generated in the combustion chamber reach the cavities 14 and 15 via the clearance space between the land 12 and the cylinder wall, the fundamental frequency wave being absorbed by the large cavities 14, and the harmonic by the smaller cavities 15. The device will be seen to operate in the nature of a Helmholtz type resonant absorber, the cavities 14 and 15 comprising the chambers of Helmholtz resonators, and the clearance space between the land 12 and the cylinder wall 13 comprising the neck. The sound wave energy of detonation is thus absorbed by resonant attenuator devices, designed to be responsive to the offensive frequencies of detonation, which are the acoustic resonant frequencies of the combustion chamber. By suppression of these resonant frequencies, the acoustic basis for the phenomena of detonation is effectively stifled.

It will be understood that the drawings and description are illustrative only, and that various changes in design, structure and arrangement may be made without departing from the invention as defined by the appended claims.

I claim:

1. A piston for an internal combustion engine having a cylinder and a combustion chamber, said piston having a cylindrical side wall formed with a setback surface at its top end, so arranged as to afford a narrow clearance space between the said surface and the confronting surface of the cylinder of an engine in which said piston is installed, and there being an acoustic cavity sunk into the side of the piston and arranged in communication with said clearance space, said cavity functioning as the acoustic cavity of a Helmholtz resonator, and said clearance space functioning as the neck of said resonator through which sound waves from the combustion chamber may reach said cavity, said cavity being frequency responsive to a detonation sound wave in the combustion chamber.

2. A piston for an internal combustion engine having a cylinder and a combustion chamber, said piston having a cylindrical side wall formed at its top end with set back surface areas, so arranged as to afford narrow clearance space between said surface areas and the confronting surface of the cylinder, and there being a series of acoustic cavities extending entirely around the piston, all arranged in communication with said clearance space, said cavities functioning as the acoustic cavities of Helmholtz resonators and said clearance space functioning as the neck for said resonators through which sound waves from the combustion chamber may reach said cavities, said cavities being frequency responsive to detonation sound waves in the combustion chamber.

3. A piston for an internal combustion engine having a cylinder and a combustion chamber, said piston having a cylindrical side wall formed at its top end with a slightly reduced cylindrical section affording a clearance space between said section and the confronting surface of the cylinder, there being an acoustic cavity sunk into the side of said cylinder in a position to communicate with said clearance space, said cavity

functioning as the acoustic cavity of a Helmholtz resonator, and said clearance space functioning as the neck of said resonator, through which sound waves from the combustion chamber may reach said cavity, said cavity being frequency responsive to a detonation sound wave in the combustion chamber.

4. A piston for an internal combustion engine having a cylinder and a combustion chamber, said piston having a cylindrical side wall formed at its top end with a slightly reduced cylindrical section affording a clearance space between said section and the confronting surface of the cylinder, said piston having a series of acoustic cavities extending entirely around the piston, all arranged in communication with said clearance space, said cavities functioning as the acoustic cavities of Helmholtz resonators and said clearance space functioning as a single neck for said resonators through which sound waves from the combustion chamber may reach said cavities, said cavities being frequency responsive to detonation sound waves in the combustion chamber.

5. A piston for an internal combustion engine having a cylinder and a combustion chamber, said piston having a side wall, there being an acoustic cavity sunk into said side wall near the top end of the piston, and a setback formation on said side wall forming a clearance space with the cylinder wall of the engine establishing restricted sound wave communication between said cavity and the combustion chamber of the engine.

6. For use with an internal combustion engine having a combustion chamber and a cylinder opening into said chamber, a piston adapted for reciprocation in said chamber, said piston having at its top end a circumscribing cylindrical surface spaced slightly from the opposed walls of said cylinder, so as to form a narrow sound wave passage, and an acoustic attenuative cavity sunk into the wall of said piston below said surface and communicating with said combustion chamber by way of said sound wave passage.

7. For use with an internal combustion engine having a combustion chamber and a cylinder opening into said chamber, a piston adapted for reciprocation in said chamber, said piston having at its top end a circumscribing cylindrical surface spaced slightly from the opposed walls of said cylinder, so as to form a narrow sound wave passage, and a ring of circumferentially spaced acoustic attenuative cavities sunk in the wall of said piston below said surface and communicating with said combustion chamber by way of said sound wave passage.

8. For use in an internal combustion engine having a combustion chamber and a cylinder opening into said chamber, a piston adapted for reciprocation in said cylinder, said piston having at its top end portion a circumscribing circumferential surface of revolution spaced from the wall surface of the cylinder, so as to form a sound wave passage, and said surface having sunk therein acoustic attenuation means presenting an attenuative acoustic response to a detonation wave frequency in said combustion chamber.
